Inventor

George Hayes

UNITED STATES PATENT OFFICE.

GEORGE HAYES, OF NEW YORK, N. Y.

SKYLIGHT.

SPECIFICATION forming part of Letters Patent No. 295,166, dated March 18, 1884.

Application filed November 7, 1881. (No model.)

To all whom it may concern:

Be it known that I, GEORGE HAYES, a resident of the city, county, and State of New York, and a citizen of the United States, have invented a new and useful Improvement in Skylights, of which the following is a specification.

The object of my invention is to provide for ventilation in a skylight without a ventilating device so constructed or so placed as to obstruct the light, as is the case when the ordinary metallic-box ventilators are used, and also to obviate the necessity of elevating the skylight upon the vertical ventilating-walls of a turret, as heretofore frequently done, which is an expensive mode of obtaining ventilation, and which construction, by removing the skylight farther away from the apartment, according to the height of the turret-walls, has the tendency to narrow the space covered by the diffused rays of light; and my invention consists in a superstructure provided for one or more sections of a skylight, (built in any of the usual styles,) the superstructure consisting of a skeleton frame filled in, where necessary, with glass, and having a face open for ventilation. The roof or top thereof would always be glazed. The sides may be glazed or filled in with sheet metal, as desired. The ventilating-face may be provided with one or more valves or louver-slats, to regulate the amount of ventilation, and exclude rain, hail, or snow from the interior. The entirety of this superstructure is above the plane of the skylight-glazing, its sides rising vertically from two of the sloping bars of the skylight, and its glazed top roofing in or covering space between the sloping bars forming its support. The space between the said bars may be partially glazed or left open, as desired. There may be as many of these ventilators applied to a skylight as desired, and added thereto after a skylight has been constructed and in use, or combined with the skylight during its construction and placed on either or all of its slopes. By the use of this ventilating device the skylight may be kept well down toward the apartment to be lighted thereby, its base-frame resting securely upon the curb at the roof, and the ventilating-outlets being above the base-frame, all metallic ventilating framing or walls below the base are dispensed with, as well as metallic boxing in

or at the ridge. A narrow ridge-bar may be used, and the skeleton frame or metal-work of the skylight may be reduced to the smallest dimensions consistent with strength, and the greatest expanse of lighting-surface obtained without in any manner affecting its ventilating qualities. The amount of ventilation secured thereby is far greater than that by the use of ridge-box ventilators, and may be fully equal to that derived from the turret method, and at much less expense.

In the accompanying drawings, Figures 1, 2, and 3 show in perspective three styles of skylight having my improvement combined therewith. It may be combined with many other shapes and kinds of skylight, and the superstructure also may be formed in other shapes than those shown, to constitute a box-70 ing which will cover an opening in the skylight, with its face adapted for ventilating purposes, so that it will be in effect a transparent ventilator.

In Fig. 1 the ventilator is shown as having 75 vertical sides, which may be glazed or not, as desired. It has a glazed top forming an inclined plane, sloping from the ridge of the skylight toward its lower or outer edge, and at its outermost extremity is provided with a vertical face for ventilation. The face is here shown as having a valve-sash pivoted in the middle of each side. This sash may be hinged or pivoted at top or bottom, if desired, as I do not confine myself to this particular 85 method of hanging the valve. Two or more valves or louver-slats may be used and be stationary or movable, as desired.

In Fig. 2 the top of the ventilator is shown with a level ridge extending outward from a 90 center, and four ventilators are thus provided, forming a four-sided or square skylight, or a transparent ventilator, as a whole. Each of the ventilating devices in Fig. 2 consists of two triangular plates of glass, framed in, sloping downward from the ventilator-ridge to a hip-bar at each angle of the skylight, which forms a base for the glass, each side of the ridge, to rest on. These two plates of glass form the top of the ventilating device. They also form 95 sides therefor. At the outermost extremity of the ridge a vertical ventilating-face is formed. Bars extending from ridge to base at the lowermost extremities of the hip-bars,

sloping with the glass and supporting their edges, form, necessarily, the ventilating-face into a triangle or gable, and the opening may be provided with a valve, as in Fig. 1, or louvered, as desired. Of course, the sides in this form of ventilator may be said to be glazed as well as the top, as the glazing is both top and sides. In a skylight of this form only two of the gable-ventilators may be used, if desired, and the remainder of the skylight glazed in, as usual.

In Fig. 3 a circular skylight is shown having four of the ventilators rising from its surface, resembling "dormers," extending outward from its center or apex, each having a vertical ventilating-face, which may be valved or louvered, as desired. They each have vertical sides rising from sloping bars of the skylight, and their tops curved or semicircular, as shown. The vertical portions may be glazed or filled in with sheet metal; but in this form glass would be preferable. The tops must be glazed with curved glass. This is a form of skylight to be used only where ventilation is desired, with a skylight having the effect of a dome light, its ornamental appearance being its chief advantage.

The forms illustrated in Figs. 2 and 3 I consider equivalents or modifications of that shown in Fig. 1.

a represents the base-frame, *b* the ridge-bar, and *c* sloping bars, of a skylight.

My improvement is not confined to any special form of skylight, as it may be used upon any slope, and is adapted to skylights constructed after the usual manner. I have given the forms shown in the drawings merely to show its application. It forms an addition which may be constructed therewith or applied thereto after such skylights have been finished and in use.

d represents the face of the superstructure; *e*, the roof or top of the same, and *f* its sides. I construct a skeleton frame of sheet metal, and extend the same over an opening in the skylight between the sloping bars thereof and ridge-bar and base-frame. The opening is

made by omitting a sheet or more of glass in constructing, or removing from a skylight already constructed and in use. The superstructure forms a covering for the opening so made, and is a raised boxing thereto when the sides *f* and top *e* are glazed in. The face *d* rises from the base-frame *a* of the skylight, and is open, but provided with valve-sash or louvers to exclude rain, hail, or snow. Louvers may be used, movable or stationary, and their faces covered with screen or perforated sheet metal or wire-gauze. There may be as many of these superstructures applied to a skylight as desired and its size and shape will admit.

Persons already having skylights on their buildings may have my improvement added thereto, if desired, and so obtain ventilation without interfering with its illuminating properties or obstructing the light, or raising the skylight from its bed upon the curb of the roof, and at but comparatively small cost; and new skylights may be constructed containing it with much less expense than any form of turf known.

What I claim as new, and desire to secure by Letters Patent of the United States, is—

1. In combination with a skylight, a skeleton frame with sides *f* and top or roof *e*, constituting a superstructure raised above the plane of the glass plates of the skylight, and having a vertical face, *d*, as a ventilator, the ventilating-face *d*, provided with valve or louver, essentially as shown, for excluding rain, hail, or snow, substantially as described.

2. In combination with the base-frame *a*, and ridge *b* and sloping bars *c*, a boxing having glazed side *f* and top or roof *e*, and having a ventilating-face *d*, the said boxing open below to the interior of the structure below the skylight, to which it constitutes a superstructure for ventilation, substantially as described and shown.

GEORGE HAYES.
